CLAIMThe ornamental design for a condiment container, as shown and described.DESCRIPTION

FIG. 1 is a front, top perspective view of a condiment container showing a first embodiment of our new design;

FIG. 2 is a front, bottom perspective view thereof;

FIG. 3 is a front view thereof; the rear view being a mirror image of the front view;FIG. 4 is a left side view thereof; the right side view being identical to the left side view;

FIG. 5 is a top view thereof;

FIG. 6 is a bottom view thereof.

FIG. 7 is a front, top perspective view of the condiment container of FIG. 1 in a condiment container set illustrated at a slightly smaller scale;

FIG. 8 is a front, bottom perspective view thereof;

FIG. 9 is a front view thereof; the rear view being a mirror
image of the front view;

FIG. 10 is a left side view thereof;

FIG. 11 is the right side view thereof;

FIG. 12 is a top view thereof; and,

FIG. 13 is a bottom view thereof.

The features shown in broken lines depict portions of the condiment container and environmental subject matter that form no part of the claimed design.1 Claim, 9 Drawing Sheets(56)
